(57) **CLAIM**

The ornamental design for a reduced-touch contamination device, as shown and described.

DESCRIPTION

FIG. 1 is a top perspective view of a reduced-touch contamination device, showing my new design.

FIG. 2 is a front side view thereof, wherein the front side is a mirror image of the rear side.

FIG. 3 is a top plan view thereof; and,

FIG. 4 is a cross-sectional isolated enlarged side view of the reduced-touch contamination device shown in FIG. 1.

The broken lines are included for the purpose of illustrating an environment, and form no part of the claimed design.
